DISPLAY STAND OR THE LIKE

George M. Child, 14509 Cullen St.,
Whittier, Calif. 90603

Filed Jan. 7, 1971, Ser. No. 104,843

Term of patent 14 years

Int. Cl. D6—06

U.S. Cl. D6—85

FIG. 1 is a perspective view of a display stand or the like showing my new design;

FIG. 2 is an elevational view taken from the side opposite that shown in FIG. 1;

FIG. 3 is a bottom plan view thereof; and

FIG. 4 is a rear elevational view thereof.

I claim:

The ornamental design for a display stand or the like, as shown.
